UNITED STATES PATENT OFFICE.

JOHN S. ROAKE, OF BROOKLYN, NEW YORK.

SOAP-HOLDER.

SPECIFICATION forming part of Letters Patent No. 757,638, dated April 19, 1904.

Application filed June 4, 1901. Renewed September 11, 1903. Serial No. 172,823. (No model.)

To all whom it may concern:

Be it known that I, JOHN S. ROAKE, a citizen of the United States, residing in the city of New York, borough of Brooklyn, in the county of Kings and State of New York, have invented a certain new and useful Improvement in Soap-Holders, of which the following is a specification.

The invention relates to that class of holders especially designed for service in lavatories and public toilet-rooms, in which the soap cake is secured to the fixed work adjacent to the basin, and while available for use is held against accidental or intentional removal by the user.

The novelty resides in the peculiarities of construction hereinafter particularly pointed out in the claims.

The accompanying drawings form a part of this specification.

Figure 1 is a vertical section, partly in elevation, showing a portion of a basin and slabs with the improved holder in place. Fig. 2 is a section through the soap cake, showing the locking device in elevation. Fig. 2' is a similar view showing the soap cake and its portion of the locking device alone. Fig. 3 is a partial section and elevation showing the locking device alone with its parts separated. It is on a larger scale than the other figures. Fig. 4 is a corresponding face view of the key used in effecting the separation. Fig. 5 is an elevation of a portion of the rear face of the back slab, showing the manner of attaching the bracket.

Similar letters of reference indicate like parts in all the figures where they appear.

A is the back slab, of slate or marble, as usual, or of other material, supported on the horizontal slab A', to which is attached the basin A'' and which may be equipped with the usual supply and waste pipes, faucets, and plug. (Not shown.)

At a point in the back slab A above the basin and preferably on its central line where the curve of the basin approaches nearest the back slab is drilled a small hole a, extending through the slab. By means of a drift or similar tool a narrow longitudinal groove a'

is produced along the inner face of the hole 50 similar to a keyway.

B is a bracket received in the hole a and extending outwardly to a line passing perpendicularly just within the margin of the basin and is provided with a shackle C, carrying a short length of chain C', again shackled at C' to the locking device D, secured to the soap cake M. The bracket at its rear end is drilled transversely and receives a pin B', extending outwardly on one side, adapted when 60 the bracket is thrust through the hole a to pass freely along the groove a', which should be deep enough to accommodate it, and when the bracket is partially rotated to engage and lie against the rear face of the slab and prevent withdrawal. The pin is held in close contact by the pull exerted by the nut B² against the opposite face of the slab.

To prevent withdrawal, by simply reversing the foregoing operation I insert a plug b of 70 wood or other material, filling the groove and lying concealed behind the nut B². Thus filled it is impossible to withdraw the bracket without first drilling away the plug or otherwise destroying or removing it. The wall behind prevents forcing the plug inward sufficiently to free the groove.

The locking device D consists of two separate portions adapted when properly presented to each other to automatically engage. One 80 of the portions is shackled to the chain C' and the other lies in the soap cake, so that when locked the cake cannot be removed from the chain until so far worn away as to allow access to the lock. In the preferred form, (shown 85 in Figs. 1 to 3, inclusive,) D' is a head receiving the shackle C' and having a flange D² lying against the adjacent surface of the cake M and a tubular extension D³ reaching into a cavity in the latter and carrying in its interior two spring-tongues D⁴ with inwardly projecting lips D⁵.

D⁶ is a button having a flange D⁷ anchored in the soap cake by embedding it during the process of manufacture at the bottom of the 90 cylindrical cavity m, extending to the exterior of the cake and having a diameter corresponding to that of the tubular extension D³, which

it is to receive. The button carries on its upper face a conical stud D⁸, undercut annularly at d and adapted to force apart the spring-tongues D⁴ when they are thrust upon it and be grasped by the lips D⁶, engaging the undercut when the head portion is pressed home. The conical shape of the stud and the annular undercut allow the soap cake to be locked to the head without requiring any special attention as to the relative positions of the parts when presented to each other. Thus engaged the parts cannot be separated and the soap cake will be securely held against removal, though conveniently supported for use.

15 The gravity of the chain and locking device with the cake causes the former to hang vertically, and as the line of suspension passes within the margin of the basin any water on the surface of the cake flowing to the lowest point will drop into the basin and not upon the slab, thus reducing the liability of the latter to become defaced or soiled.

While any considerable bulk of the soap remains the cake cannot be removed, because 25 the locking engagement is within it and hidden; but when the cake is worn away the parts may be separated by inserting the key G into the keyhole d², and by turning in either direction the wings G', striking the inner 30 faces of the tongues D⁴, will separate them sufficiently to release the stud D⁸ and allow the button to be removed and a fresh cake applied and held in the same manner.

The spring-tongues D⁴ are preferably 35 formed of a single strip of spring-brass or other metal folded upon itself and secured in a score in the head D⁷ by a single pin D⁹, which also secures the tubular extension D³ to the head and makes a simple and inexpensive mode 40 of fastening both. The buttons may be formed in large quantities by automatic machinery, and thus inexpensively produced.

The flexible connection allows the soap cake to be readily held aside, if in the way, by 45 simply winding the chain upon the bracket.

The shoulder D¹⁰ on the button performs an important function in preventing lateral movements of the button and head relatively to each other by its engagement within the 50 lower end of the tubular extension D³, and thus guards against efforts to effect separation by forcing the head in one direction or the other sufficiently to disengage the tongue

from the stud. The spring-tongues D⁴ are protected by the inclosing tubular extension D³ and are therefore not likely to be accidentally broken or bent when the parts are in the separated condition.

I attach importance also to the depression or hollow d¹¹ on the under face of the button. It fills with soap during the process of molding and further increases the hold of the button upon the inclosing soap cake and prevents change of position therein.

Although I have shown a spherical soap cake 65 and prefer that shape, it will be understood that the cake may be of any shape, provided the locking device conforms as to length and other requirements.

I claim—

1. The bracket B and pin B' on the inner end thereof, the slab A having a hole a and groove a' therein receiving said inner end and pin, the plug b filling said groove, and the nut B² drawing said pin against the rear face 75 of said slab and also concealing said plug, combined with a flexible ligament suspended from the outer end of said bracket, substantially as and for the purpose specified.

2. As an improved article of manufacture, 80 a soap cake formed with a cavity therein, a button located within and inclosed by the soap and having a depression in its under face, a flange, and a conical stud opposite said depression undercut below, a head having means 85 whereby it may be supported by a chain, a flange on said head, a tubular extension from the latter, two spring-tongues having inwardly-projecting lips inclosed in said extension and adapted to be separated by said stud and engage in said undercut, said extension being inserted in the cake and locked thereto by the inclosed button, the said head being provided with a keyhole to permit the insertion of a key between said spring-tongues to allow 90 separation of said head and button when said cake is worn away, all substantially as shown and described.

In testimony that I claim the invention above set forth I affix my signature in presence of two witnesses.

JOHN S. ROAKE.
